UNITED STATES PATENT OFFICE.

THOMAS HANNEY AND JOHN H. BECKER, OF BROOKLYN, NEW YORK, ASSIGNEES TO
WARP TWISTING-IN MACHINE COMPANY, OF BROOKLYN, NEW YORK, A CORPORA-
TION OF NEW YORK.

WARP-CONTROLLED CONTROLLING MEANS FOR LOOMS.

Application filed October 6, 1923. Serial No. 666,901.

To all whom it may concern:

Be it known that we, THOMAS HANNEY and JOHN H. BECKER, citizens of the United States, residing at Brooklyn, in the county 5 of Kings and State of New York, have invented certain new and useful Improvements in Warp-Controlled Controlling Means for Looms, of which the following is a specification.

10 In looms having warp-controlled electromagnets to do certain work, as to cause stopping of the loom when a warp-thread breaks or becomes unduly slack, it is necessary to provide at present space for the system of
15 fallers or other controlling devices for the circuit, which thus encumber the loom, and there is the further disadvantage that the harness cannot be taken from the loom along with the warp (so that the loom can be con-
20 tinued in operation with another harness and warp) because of the engagement of the warp threads with the several controlling devices, which are not conveniently de-
25 mountable from the loom. Therefore it has been proposed to place the controlling de-
vices in the heddle-frames of the harness, and it is to this class of warp-stop motions in particular to which our invention relates. The principal object of the invention is to
30 provide a heddle-frame containing the fallers as well as the heddles and having the former kept against tilting forward or back, when they fall, out of the plane in which they are suspended and so into the way of
35 an adjoining heddle-frame by means entirely below the eyes or equivalent warp-thread-engaging portions of the fallers, so that the upper ends of the fallers are unguided and free. This construction makes possible a
40 very material reduction of the weight that is added to the heddle-frame when the fallers are arranged therein, for the fallers need only be of such length as to extend upwardly approximately to the middle (measured vertically) of the heddle-frame. Our invention further contemplates constructing the parts of the improved mechanism which are to be carried by the heddle-frame so that they will be inexpensive to manufacture and
45 capable of ready application to heddle-frames in common use.

In the accompanying drawings,

Fig. 1 is a front elevation of a common form of heddle-frame equipped with the

parts constituting this invention in one form 55 thereof;

Figs. 2 and 3 are sectional views on the line 2—2, Fig. 1, illustrating the two different positions of a faller;

Fig. 4 is a horizontal sectional view 60 through the trough forming member 1;

Fig. 5 shows a faller in front and side elevation;

Fig. 6 shows a fragment of the heddle-frame equipped with the parts constituting 65 our invention in another form thereof; and

Fig. 7 is a sectional view on line 7—7, Fig. 6.

The heddle-frame shown comprises the usual top and bottom rails *a b*; the metal side or end bars *c* connecting the ends of these rails; the top and bottom bars *d e* on which the heddles *f* having eyes *f'*, are strung, these bars being kept taut by the usual spring clips *g*; and the top and bottom rods *h i* which are mounted in eyes *j* driven into the rails and carry hooks *k* which engage the heddle-bars *d e* at intervals to reinforce them against the strain of the warp 80 as the frame reciprocates vertically.

Referring, first, to Figs. 1 to 5: In the lower part of the heddle-frame, to wit, just above the bar *e*, and in a plane to one side of that of the heddles *f* is arranged a horizontal strip *l* forming a trough *l'* in which, at 85 the bottom thereof, is arranged a pair of spaced terminal bars *m* extending lengthwise of the trough and insulated from each other. The terminal bars may be and in this construction preferably are insulated from each other by forming the strip *l* of insulating material and setting them in the same. The ends of the strip abut the inner faces of the side or end bars *c* of the frame and may be rigidly secured thereto by screws *n* or otherwise. One end of said strip may have a projection *l*² which extends through a hole in the corresponding side or end bar and through which project the ends of the terminal bars, which are equipped with binding posts or equivalent means *o* for attaching thereto the ends of the conductor *p* of a circuit including a source of energy *p'* and an electro-magnet *p*² whose armature *p*³ forms the element to be actuated when the 95 breaking or slackening of a thread *A* occurs. Above the strip *l* and made to connect the side or end bars *c* in any way in a horizontal 100 105

bar q . Both the strip l and this bar, it will be noted, are below the horizontal plane of the warp-guiding portions or eyes f' of the heddles. Each faller r is a strip of metal having an eye r' at one end for the reception of a warp thread and at the other end a contact nub r^2 , which is preferably a rounded projection extending from one face of the strip, being rounded around a horizontal axis 10 parallel with the plane of the strip; between its ends, but nearer the end having the nub r^2 , a slot r^3 is formed by slitting the strip longitudinally and then bending the metal both sides of the slit in opposite directions 15 out of the main plane of the strip. Each faller is arranged in the heddle-frame as shown best in Figs. 2 and 3, to wit, so that the bar q penetrates its slot r^3 and its lower end is received in the channel or trough of strip l . When the heddles are to be threaded with the warp threads A each faller is raised so that its eye r' registers with the eye f' of the corresponding heddle and both eyes are threaded at once. When the loom is operating 20 the tension of the warp of course maintains all the fallers elevated as in Fig. 2 so long as none of the warp threads breaks or becomes unduly slack; in either of these eventualities the faller affected will fall and its nub r^2 will contact with the bars m , closing the circuit. The nub is rounded in the specific way described so that in any cross-section thereof in a vertical plane transverse 25 of the portions forming the sides of the trough it has the same thickness; thus, since it is nearly as thick as the channel of the trough is wide, it serves to keep the faller from assuming a skewed position or always faced substantially as shown in Fig. 1.

40 In Figs. 6 and 7 the channel or trough for the lower ends of the fallers is formed in the lower rail of the heddle frame, the construction of the entire structure being the same, except in the particulars now to be indicated, as that already described. This rail has a rabbet s formed in one vertical face thereof at the top and extending nearly to each end thereof and this is covered by an elongated strip t which may be secured to the rail by screws u and has a rib t' at the inside which rests on the bottom surface of the rabbet and in which is set the pair of terminal bars v . These terminal bars are equipped with the binding posts w for the circuit conductor p , and the end of one is bent up and over the other as shown in Fig. 6 so as to bring both binding posts as near as possible in the same vertical plane, said ends being set in insulation x where they penetrate the side or end bars c . The strip t , as well as the rail b (which is of wood), are insulative.

50 In both constructions the weight which is added by incorporating the fallers in the heddle-frame is reduced approximately one-half by arranging the means which keeps the

fallers against tilting forward or backward when they fall (to wit, bar q and the trough) below the eyes r' of the fallers. The nubs r^2 on the fallers, by desirably weighting them at their lower ends and by being rounded, insure certain contact of the fallers with the terminal bars. 70

Having thus fully described our invention, what we claim and desire to secure by Letters Patent is:

1. In combination, a heddle-frame, heddles arranged in the heddle-frame and having warp-thread guiding portions, and vertically elongated circuit-closing fallers having free upper end portions and means in said end portions to suspend the fallers from the warp-threads, said frame having, below said portions of the heddles, means to sustain each faller upon falling in substantially the plane, transverse of the warp, in which it is suspended. 80

2. In combination, a heddle-frame, heddles arranged in the heddle-frame and having warp-thread guiding portions, and vertically elongated circuit-closing fallers having free upper end portions and means in said end portions to suspend the fallers from the warp-threads, said frame having, below said portions of the heddles, separate means, arranged at different elevations and below said portions of the heddles, to sustain each faller upon falling in substantially the plane, transverse of the warp, in which it is suspended. 90

3. In combination, a heddle-frame, heddles arranged in the heddle-frame and having warp-thread guiding portions, and vertically elongated circuit-closing fallers having free upper end portions and means in said end portions to suspend the fallers from the warp-threads, said frame having, below said portions of the heddles, means to sustain each faller upon falling in substantially the plane, transverse of the warp, in which it is suspended, and said last-named means including, vertically below each faller, a trough in which the faller is adapted to fall. 100

4. In combination, a heddle-frame, heddles arranged in the heddle-frame and having warp-thread guiding portions, and vertically elongated circuit-closing fallers having free upper end portions and means in said end portions to suspend the fallers from the warp-threads, said frame having, below said portions of the heddles, means to sustain each faller upon falling in substantially the plane, transverse of the warp, in which it is suspended, and said last-named means including, vertically below each faller, a trough in which the faller is adapted to fall 110 and, above the trough, a bar engaged by the several fallers. 120

5. In combination, a heddle-frame, heddles arranged in the heddle-frame and having warp-thread guiding portions, and verti- 130

cially elongated circuit-closing fallers having free upper end portions and means in said end portions to suspend the fallers from the warp-threads, said frame having, below said portions of the heddles, means to sustain each faller upon falling in substantially the plane, transverse of the warp, in which it is suspended, and said last-named means including a trough-forming member removably secured to the remaining part of the frame with its trough vertically below each faller and adapted to receive the latter when it falls.

6. In combination, a heddle-frame having a lower rail, heddles arranged in the heddle frame and having warp-thread guid-

ing portions, and vertically elongated circuit-closing fallers having free upper end portions and means in said end portions to suspend the fallers from the warp-threads, 20 said frame having, below said portions of the heddles, means to sustain each faller upon falling in substantially the plane, transverse of the warp, in which it is suspended, the last-named means including, 25 vertically below each faller, a trough formed in said lower rail and into which the faller is adapted to fall.

In testimony whereof we affix our signatures.

THOMAS HANNEY.
JOHN H. BECKER.
